UNITED STATES PATENT OFFICE.

MARTIN D. MIESNER, OF ALTENBURG, MISSOURI.

COMBINED TABLE AND BED.

1,252,713.

Specification of Letters Patent. Patented Jan. 8, 1918.

Application filed February 4, 1915. Serial No. 6,143.

To all whom it may concern:

Be it known that I, MARTIN D. MIESNER, a citizen of the United States, residing at Altenburg, in the county of Perry and State 5 of Missouri, have invented certain new and useful Improvements in Combined Tables and Beds, of which the following is a specification.

My invention relates to new and useful 10 improvements in furniture and more particularly to a combined table and bed.

The primary object of the invention is the provision of a piece of furniture which is ornamental in construction and which 15 may be easily converted from a table to a bed or from a bed to a table.

A further object of the invention is the provision of means for holding the several parts in their various positions.

20 A still further object of the invention is the provision of means for automatically converting the table to a bed when the catch is released.

With these and other objects in view the 25 invention consists in the novel details of construction and arrangement of parts which will be more clearly understood from the following description and drawings, in which,

30 Figure 1 is a view in side elevation showing my improvements when used as a table.

Fig. 2 is a perspective view showing my invention converted into a bed construction.

Fig. 3 is a transverse section when used 35 as a table.

Fig. 4 is a fragmental detail of the catch, and

40 Fig. 5 is a fragmental detail in side elevation showing the raising and supporting means for the table leaf when used as a bed.

In the drawings, the numeral 1 indicates the side pieces of the frame and 2 the end piece of the frame. The frame is supported 45 at each corner upon a leg 3 and a shelf 4 is connected to the legs at a point intermediate the ends of the legs and the frame. Vertical openings 5 are formed in the side pieces 1 of the frame and terminate into

an enlarged opening 6, more clearly shown 50 in Fig. 4 of the drawings and the purpose of which will be later described. Secured to and extending longitudinally of the side pieces 1 are the vertical strips 7 and said strips are so spaced from the inner edge of 55 the strips 1 as to leave a space to receive and support the angle iron strips 8, more clearly shown in Fig. 3 of the drawings, to which are secured the spring fabric 9. Supported upon the spring fabric is the matress 10, as also clearly shown in Fig. 3 of the drawings.

A rod 11 extends transversely through the side pieces 1 and is provided with an enlarged head 12 on one end thereof, as more 60 clearly shown in Fig. 4 of the drawings. This enlarged head is adapted to be received within a socket or recess 13 formed in the side of one of the strips 1. This rod 11 is provided near either end thereof with 70 an upwardly extending hook 14, the purpose of which will be presently described. The hook is received and operates in the opening 6 in the piece 1. A collar 15 is secured near one end of the rod 11 and a coil spring 16 75 surrounds the rod between the collar and side piece 1. This coil spring is adapted to normally hold the enlarged head 12 of the rod 11 to its forwardmost position.

Hingedly connected to the end strips 2 80 of the frame are the leaf members or top sections 17 and 18. The section 17 is provided with a transverse groove 19 which is adapted to receive the transverse tongue 20 formed on the section 18 when the sections 85 are lowered and being used as a table. The sections 17 and 18 are each provided with the downwardly extending side strips 21 and end strips 22. The side and end strips are adapted to rest upon the strips 1 and 2 90 when my invention is being used as a table. When used as a table the side strips 21 are on the outside of the vertical strips 7 thereby hiding the same from view. Pivottally connected links 23 are connected to the strips 95 7 and side strips 21 of the top sections 17 and 18 and act as a support for the said sections when raised to be used as a bed.

Secured to the frame and to the end pieces 22 are the springs 24 which are placed under tension when the top sections are lowered.

Hooks 25 are connected to the side pieces 21 of the top section 18 and when the section is lowered pass through the openings 5 and engage the hooks 14 on the rod 11. In lowering the sections 17 and 18 it will be understood that the section 17 is first lowered and then the section 18 whereby the transverse tongue 20 on the section 18 will enter the groove 19 in the section 17. It will also be seen that the section 18 having the hooks 25 will hold the section 17 in lowered position.

Having fully described the detailed construction of my device it is thought that the operation will be clearly understood. When the parts are in the position, as shown in Fig. 1 of the drawings, my invention is adapted to be used as a table. The mattress, springs, and other details of the invention are inclosed within the top sections and are out of view when my invention is being used as a table. The tongue 20 entering the groove 19 prevents any water or other liquids which might be spilled upon the table-top from entering beneath the top and thereby falling upon the mattress. When it is desired to use my invention as a bed, it is only necessary to press upon the enlarged head 12 of the rod 11. This releases the hooks 14 from the hooks 25 and the sections 17 and 18 are automatically raised by means of the springs 24. When in their raised position the sections 17 and 18 are held and braced by means of the pivoted links 23.

When it is desired to reconvert the furniture into a table the top section 17 is first lowered and then the section 18. The hooks 25 are then brought into engagement with the hooks 14 and the sections held in their lowered position. It will be understood that the spring 16 surrounding the rod 11 returns the rod to its normal or first position after the enlargement 12 has been pushed. The hooks 14 are therefore always in position to be engaged by the hooks 25 when the sections are lowered.

From the above it will be seen that I have provided a piece of furniture which may be very easily converted from a table to a bed or from a bed to a table. It will be further noted that when it is being used as a bed there is no chance whatever for the sections closing upon the occupant. The springs 24 hold the sections in raised position and the pivotally connected links 23 also act as a brace to prevent the accidental lowering of the sections. The springs and mattress resting upon the side strips 1 and end strips 2 can be readily removed for airing or cleaning and can then be replaced in position. I

have also provided a sufficient space between the top sections and the mattress to accommodate the pillows which are used. 65

Having fully described the invention what I claim as new and desire to secure by Letters Patent is:—

1. A combined table and bed comprising 70 a frame, a rod extending transversely of the frame, hooks secured to the rod, top sections hingedly connected to the frame, and hooks carried by one of said top sections and adapted to engage the hooks on the transverse rod.

2. A combined table and bed comprising 80 a frame, a slidable rod extending transversely of the frame, hooks secured to the rod, top sections hingedly connected to the frame, and hooks secured to one of said top sections and adapted to engage the hooks on the sliding rod.

3. A combined table and bed comprising 85 a frame having vertical openings formed in the top thereof and terminating in enlarged openings, a slidable rod extending transversely of the frame, hooks secured to said rod and operating in said enlarged openings of the frame, top sections hingedly connected to the frame, and hooks connected to one 90 of said sections and adapted to enter the openings in the frame and engage the hooks on the rod.

4. A combined table and bed comprising a 95 frame, a slidable spring controlled rod extending transversely of the frame, hooks formed on the rod, top sections hingedly connected to the frame, hooks secured to one 100 of said top sections and adapted to engage the hooks on the rod when the sections are lowered, and springs connected to the frame and top sections for automatically raising the sections when the hooks on the rod are disengaged from the hooks on the sections. 105

5. A combined table and bed comprising a frame, and top sections hingedly connected to the frame, one of said sections provided with a transverse groove and the other section provided with a transverse tongue 110 adapted to enter the groove.

6. A combined table and bed comprising a frame having openings formed in the top thereof and terminating into enlarged openings, a rod extending transversely of the frame, hooks formed on said rod and operating in the enlarged openings, top sections hingedly connected to the frame and one of 115 said sections overlapping the other, and hooks connected to said overlapping section 120 and adapted to enter the openings in the frame and engage the hooks on the transverse rod.

7. A combined table and bed comprising a frame having vertical openings in the top 125 thereof terminating into enlarged openings

and transverse openings through the sides of the frame intersecting the vertical openings, a rod slidably mounted in the transverse openings, hooks formed on the rod and operating in the enlarged openings, vertical strips secured to the top of the frame, spring-controlled top sections hingedly connected to the frame, braces pivotally connected to the top sections and vertical strips, and hooks secured to one of said top sections and adapted to engage the hooks on the transverse rod. 10
In testimony whereof I affix my signature in presence of two witnesses.

MARTIN D. MIESNER.
